MACHINE FOR POSITIONING STRING
HANDLES ON BAGS

Carleton G. Eaton, Waltham, and Alfred J. Thomas, Braintree, Mass., assignors to A. M. Eaton Paper Company, Boston, Mass., a corporation of Massachusetts

Application June 17, 1937, Serial No. 148,704

7 Claims. (Cl. 93—8)

This invention relates to the manufacture of bags and more particularly to mechanism for placing a desired length of string in position upon a bag to be secured to the latter and serve as a handle.

A mechanism of that general character is described in the United States patent to Carleton G. Eaton, No. 1,762,857, dated June 10, 1930. The present invention is directed to improvements in mechanism of this type which make possible a reduction in the time required for securing string handles upon bags.

The invention will be more clearly understood from the following description in conjunction with the accompanying drawings: in which:

Fig. 1 is a front elevational view of a machine embodying the invention;

Fig. 2 is a plan view of the same, partly broken away;

Fig. 3 is a side elevational view of the same;

Figs. 4, 5 and 6 are detail plan views of a portion of the machine showing the relationship of the parts at different stages of the operation of the machine;

Figs. 7 and 8 are sectional elevational views of the portion of the machine shown in Figs. 4, 5 and 6;

Figs. 9, 10 and 11 are fragmentary sectional detail elevational views of different portions of the machine; and

Fig. 12 is a perspective view of a bag having handles secured to the open end thereof by the mechanism embodying the invention.

Before explaining in detail the present invention, it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

In general, a machine embodying the invention comprises a stapling mechanism S (Figs. 1 and 3) adapted to secure string handles H upon a bag B, such as a paper shopping bag (Fig. 12).

A mechanism P (Figs. 2 to 8 inclusive) is provided for positioning the string handle H with respect to the bag B. String is supplied to the positioning mechanism P from a supply roll R (Fig. 2) from which it is withdrawn by a mechanism W (Figs. 1, 2 and 3) and fed intermittent-

ly by a mechanism F (Fig. 1) to the positioning mechanism P. After being fed to the positioning mechanism P the string is cut to the desired length of the handle H by a cutting mechanism C (Figs. 1 and 10).

Any suitable stapling mechanism may be employed in the practice of the invention, the specific construction being unimportant and forming no part of the present invention. As illustrated in the accompanying drawings the stapling mechanism S is carried by a frame 10 (Figs. 1 and 3) having a forwardly extending portion 11 at its upper end. Depending from the forward end of the frame portion 11 is a fastener forming and applying mechanism 12 adapted to place four fasteners 13 in a bag B to secure a string handle H thereto as illustrated in Fig. 12. The mechanism 12 is actuated by power supplied from a shaft 16 which is rotatably mounted in bearings in the frame portion 11. Power is supplied to rotate the shaft 16 by a belt 17 engaging a pulley 18 which is rotatably mounted upon the shaft 16 and adapted to be connected in driving relation thereto by a clutch 19 rendered operative by a rod 20 which is connected to an operating treadle (not shown). Below the frame portion 11 a pair of spaced frame members 25 extend forwardly from the frame 10 and are connected at their forward ends by a platform 26 positioned beneath the mechanism 12. The platform 26 is provided with a pair of spaced clinching blocks 27 adapted to cooperate with the mechanism 12 for applying fasteners to the bag. The platform 26 also is provided with a pair of stops 28 for positioning a bag with respect to the mechanism 12.

In accordance with one embodiment of the invention the positioning mechanism P may comprise guideways 30 (Figs. 4 to 8 inclusive) at opposite edges of the platform 26 so as to slidably guide a slide 31 forward and rearward. The rear end of the slide 31 is connected to one end of a rod 32 the other end of which is pivotally connected to one end of a bell crank lever 33 pivotally carried upon a bracket 34 fixed upon the frame 10. The other end of the bell crank lever 33 is provided with a cam follower 35 adapted to engage a cam groove 36 formed in a disc 37 fixed upon the shaft 16.

A pair of spaced bars 40 are slidably mounted in grooves formed in the surface of the slide 31. The forward ends of the bars 40 are turned downward to provide cam surfaces 41 for a purpose described hereinafter. Adjacent the cam surfaces 41 and immediately rearward thereof 55.

the bars 40 are connected by a string support 42 which extends laterally beyond the opposite edges of the platform 26. Immediately in the rear of the string support 42, the bars 40 are connected 5 by a cross member 44 extending upwardly beyond the top surface of the support 42. Secured to the member 44 and extending forwardly therefrom over the support 42 and in spaced relation to the latter are a pair of spaced fingers 45. A 10 U-shaped member 46 is suitably secured to the slide 31 in a position so that its spaced parallel portions 47 may be moved past the ends of the member 44. A friction block 50 extends between and rests upon the bars 40. The friction block 15 50 is secured upon the slide 31 by screws 51 passing through holes in the block 50 and engaging the slide 31. A spring 52 surrounds each screw 51 with one end engaging a washer 53, the upper position of which is limited by the head of the 20 screw.

A templet 55 is pivotally mounted at its forward end upon the platform 26 and is adapted to move into and out of its operative position in a plane lying in the path of movement of the presser member 44 and U-shaped member 46. A rod 56 is pivotally connected at its upper end to the templet 55 and extends downwardly through a passage 57 in the platform 26. The rod 56 is urged axially downward by a spring 58 surrounding the same and with one end engaging the bottom of the platform 26 and its other end engaging a washer 59 held upon the lower end of the rod 56. The downward movement of the rod 56 causes the templet 55 to pivot out of its operative position to a position limited by engagement between the top surface of the platform 26 and a collar 60 fixed upon the rod 56.

A pair of stops 65 are fixed upon a cross member 66 connecting the spaced frame members 40 25. The stops 65 are positioned in the path of movement of the bars 40 and limit the rearward position thereof and the position of the string support 42 when the slide 31 is moved rearward. A string guide 68 extends between 45 and is slidably mounted in spaced guideways 69 and is adapted to rest upon the string support 42 when the latter is in its rearward position as illustrated in Fig. 4. The string guide 68 is provided with a groove 14 adjacent the support 42 and at its right-hand end as viewed in Fig. 4, the groove 14 is enlarged to provide a string entrance passage. An arm 70 is pivotally mounted at its rear end upon each of the spaced frame members 25 and is provided at its forward end with a tongue 71 adapted to engage a slot 72 formed in the string guide 68. Each of the arms 70 is provided with a cam surface 73 adapted to be engaged by a cam 74 carried by the slide 31 to pivot the arms 70 and raise 55 the string guide 68 out of engagement with the string support 42 as shown in Fig. 8.

The roll R of string is carried by a spool 75 which is mounted for rotation in spaced arms 76 depending from a frame structure 77 extending laterally from the main frame 10. The string T is drawn from the roll R and travels around a pulley 78 rotatably carried at one end of an arm 79 the other end of which is pivotally mounted upon the end of the long arm of a lever. 80. The lever 80 is pivotally mounted upon a bracket 81 fixed to a suitable support 15, such as the floor of a building. The short arm of the lever 80 carries a brake 82 adapted to engage the spool 75 to resist rotation thereof. 75 The weight of the long arm of the lever 80 tends

to swing the lever so as to bring the brake 82 into engagement with the spool 75. If desired, the long arm of the lever may be weighted in order to bring about this desired result.

The mechanism W is actuated by a shaft 85 which is rotatably supported near one end in a bearing formed in a fitting 86 secured upon the frame 77. The shaft 85 is rotatably supported near its other end in the upper bearing provided by a fitting 88 secured upon the frame 10 17. A gear 90 is fixed upon the rear end of the shaft 85 and is adapted to engage a sector gear 91 fixed upon a shaft 92 rotatably supported in the lower bearing of the fitting 88. The shaft 92 also carries a sprocket 93 driven through a 15 chain 94 from a sprocket 95 fixed upon the rear end of the shaft 16.

A pulley 96 is fixed upon the shaft 85 and is provided with a V-shaped groove 97 adapted to receive a single convolution of the string T. 20 From the pulley 96 the string T extends through a guide 98 fixed upon the frame 77 and thence passes around a pulley 99 carried at the upper end of a weight 100 which is slidably carried in a guide 101 fixed upon the support 15. The 25 weight 100 is provided within a pin 102 adapted to engage a slot 103 in the guide 101 and thus is prevented from turning in the guide. From the pulley 99 the string T extends into the intermittent feeding mechanism F.

The mechanism F comprises a tube 105 carried by a frame structure 106 secured upon the fitting 86. The tube 105 is provided with longitudinally extending diametrically opposite slots 104 and 119 and is positioned in alignment and 35 adjacent to the string guide 68 when the latter is resting upon the string support 42 of the positioning mechanism P. The string T extends from the pulley 99 through a string guide 107 and thence through a string straightening device 108, both of the latter being carried by the frame 106. After passing through the string straightening device 108, the string extends into the tube 105.

A sleeve 110 surrounds and is slidably mounted 45 upon the tube 105 and is adapted to be reciprocated upon the latter. A plate 160 fixed on the sleeve 110 projects through the slot 104 into the tube 105. The inner edge of the plate 160 is provided with teeth 161 projecting in the direction of feed of the string T and adapted to engage the latter. One end of an arm 111 is provided with a yoke 93 which is suitably connected to the sleeve 110. The other end of the arm 111 is pivotally mounted upon a stud 112 (Fig. 3) 55 carried by the fitting 86. Intermediate its ends the arm 111 is provided with a longitudinally extending slot 113 adapted to be slidably engaged by a block 109 rotatably mounted upon an eccentric pin 114 carried by a disk 115 which is suitably fixed upon the front end of the shaft 85. Preferably the pin 114 is adjustable on the disk 115 radially thereof.

A bell crank 116 (Figs 1 and 11) is pivotally mounted upon an ear projecting from the sleeve 65 110 so that one arm 117 thereof extends through the slot 118 in the sleeve 110 and through a slot 119 in the tube 105. The end of the arm 117 is provided with teeth 120 projecting toward and in the direction of feed of the string T. The other arm 121 of the bell crank 116 carries a roller 122 adapted to engage either the upper or lower surface of a guide rail 123 carried by brackets 124 fixed upon the frame 106. Another arm 130 extends from the hub of the bell crank 70 75 116.

116 and is connected at its outer end to one end of a spring 131 the other end of which is connected to a post 132 fixed upon the sleeve 110. The spring 131 tends to rotate the bell crank 5 116 in a counter-clockwise direction as viewed in Figs. 1 and 11 thereby tending to urge the teeth 120 in engagement with the string T, and hold the latter in engagement with the teeth 161 on the plate 160 which is fixed on the sleeve 10 110. The left-hand end as viewed in Fig. 1 of the guide rail 123 is provided with a downwardly inclined portion 135. Spaced from the other end of the guide rail 123 is a guide rail extension 123' carried by a bracket 136 fixed upon 15 the frame 106. The extension 123' is provided with a downwardly inclined portion 87.

Movement of the string T in the tube 105 to the right as viewed in Figs. 1, 2 and 11 is prevented by the engagement of teeth 137 formed 20 upon the end of one arm of a bell crank 138 which is pivotally carried upon an ear extending upwardly from a sleeve 139 fixed upon the tube 105, preferably, between the guide rail 123 and the cutting mechanism C. The other arm of 25 the bell crank 138 carries a weight 140 tending to rotate the bell crank in a counter-clockwise direction as viewed in Figs. 1 and 9 and urge the teeth 137 in engagement with the string T.

The cutting mechanism C (Figs. 1 and 10) 30 comprises a cutting blade 145 slidably mounted in a guideway 146 carried by and depending from a block or sleeve 147 secured upon the end of the tube 105 adjacent the thread guide 68 so that the end of the tube 105 may cooperate with the 35 blade 145 to cut the string T. A bell crank 148 is pivotally mounted on a bracket 149 secured to the guideway 146. The short arm 150 of the bell crank 148 is pivotally secured to a block 151 fixed upon the blade 145. The long arm 152 of the bell crank 148 is pivotally connected to one end of a rod 153 which extends substantially parallel to the tube 105 and is connected 40 at its other end to an ear 154 formed on a sleeve 155 which surrounds and is slidably mounted upon the tube 105. A coil spring 156 surrounds the tube 105 with one end engaging an edge of the sleeve 155 and its other end engaging a 45 portion of the frame 106.

In the operation of the machine the operator 50 positions a bag B with its open end receiving a portion of the platform 26 and with the edge of the bag engaging the stops 28 as illustrated in Fig. 4. If desired a stop (not shown) may be provided for locating the position of the bag laterally with respect to the stapling mechanism S, but this is not necessary inasmuch as the bag 55 may be positioned with sufficient accuracy in this respect by an experienced operator. The operator then steps on the treadle to operate the clutch 19 to supply power to rotate the shafts 16 and 35. During the rotation of the shaft 16, the cam groove 36 in the cam disk 37 actuates the bell crank 33 (Fig. 3) to move the rod 32 and reciprocate the slide 31 between the positions 60 shown in Figs. 4 and 6. When the slide 31 is in the position shown in Figs. 4 and 7 the string guide 68 rests upon the thread support 42 and its groove 14 is in alignment with the passage in the tube 105.

70 The operation of the mechanism is so timed that when the slide 31 is in the position shown in Fig. 4, the arm 111 is actuated to cause the sleeve 110 to move to the left as viewed in Figs. 1, 2 and 11. In so doing the roller 122 moves down the incline 75 87 and engages the bottom of the rail 123' to

cause the teeth 120 to engage the string T and hold the latter in engagement with the teeth 161 whereby the string is fed axially in the tube 105 and caused to enter the groove 14 on the bottom of the string guide 68 and rest upon the string support 42. During the movement of the sleeve 110 in this direction the spring 131 urges the bell crank 116 counterclockwise to insure positive engagement between the teeth 104 and 120 and the string T. As the string is thus moved it slides 10 beneath the teeth 137 formed upon one arm of the bell crank 138. However, the teeth 137 are directed so as to grip the string if it tends to move in the opposite direction, that is, toward the right as viewed in Figs. 1, 2, 9 and 11. 15

As the sleeve 110 moves in the opposite direction, that is, to the right as viewed in Figs. 1, 2 and 11, the roller 122 carried by the bell crank 116 engages the inclined end portion 135 of the guide rail 123 and is caused to move along the top 20 surface of the latter and maintain the teeth 120 out of engagement with the string. As the roller 122 drops off the end of the rail 123 it strikes the incline 87 and is caused to move along the top surface of the rail 123' to maintain the teeth 120 25 out of engagement with the string. As the movement of the sleeve 110 is continued in this direction it strikes the sleeve 155 causing the latter to move to the right as viewed in Fig. 1 against the action of the spring 156. This movement of the 30 sleeve 155 moves the rod 153 to actuate the bell crank 148 and move the knife blade 145 upwardly to cut the string T thus leaving upon the thread support 142 a predetermined length of string H.

As the sleeve 110 moves in the opposite direction, that is, to the left as viewed in Fig. 1, it moves out of engagement with the sleeve 155 and the spring 156 returns the sleeve 155 to its original position and thus restores the cutting mechanism to its original or inoperative position. During 40 this movement of the sleeve 110 and after the sleeve 155 is returned to its original position the roller 122 is urged downwardly along the inclined portion 87 of the guide extension 123' and is permitted to move under the guide rail 123 thereby 45 permitting the spring 131 to urge the teeth 120 toward the teeth 161 and positively grip the string T therebetween. This insures that the string T is fed the same distance during each of the intermittent feeding operations. 50

As the string T is fed through the tube 105 toward the left as viewed in Fig. 1 and as above described, it takes up the slack in the portion engaged by the pulley 99 and causes the latter together with the weight 100 to be raised. At the 55 same time the slack in the portion of the string T engaged by the pulley 78 is taken up. This action brings the string into driving relation with the pulley 96 and causes the latter to move the string first to pivot the lever 80 and move the 60 brake 82 out of engagement with the spool 75 and then to withdraw string from the roll R. The withdrawal of string from the roll R continues until the feeding of the string through the tube 105 ceases and until the weight 100 and 65 lever 80 have returned to their original positions to provide slack portions of string between the feeding mechanism F and mechanism W and between the mechanism W and the roll R.

After the string has been fed upon the string 70 support 42 and under the string guide 68 and has been severed by the cutting mechanism C to provide a length of string H resting upon the string support 42 as above described, the slide 31 is still 75 in the position illustrated in Fig. 4. The slide 31

now begins to move forward toward the position shown in Fig. 5. During this forward movement of the slide 31, the cams 74 engage the cam surfaces 73 upon the levers 70 to cause the latter to lift the string guide 68 from the position shown in Fig. 7 to that shown in Fig. 8. Thereafter, the forward movement of the slide 31 continues and the cam surfaces 41 engage the rear edge of the templet 55 to move the latter into the path of movement of the presser member 44. Then the string H is pressed in engagement with the rear edge of the templet 55 by the member 44.

It will be understood that the fingers 45 extend into the string guide 68 above the string and prevent the latter from being removed from the string support 42 as the string guide 68 is moved from the position shown in Fig. 7 to that shown in Fig. 8. As the slide 31 continues its forward movement the normal tendency is for the member 44 to rest against the back edge of the templet 55. However, the friction block tends to cause the member 44 to move forward with the slide 31 and, consequently, the member 44 exerts a substantial pressure holding the string against the templet. As the forward movement of the slide continues the spaced parallel portions 41 of the U-shaped member 46 engage the ends of the string section H and move them into engagement with the parallel sides of the templet 55 and with the ends 30 of the string H overlapping the edge of the bag as shown in Fig. 6. The stapling mechanism S is then actuated to apply the staples 13 to secure the handle H to the bag.

Thereafter, the slide 31 moves rearwardly from the position shown in Fig. 6 to the position shown in Fig. 4. As the slide 31 approaches the position shown in Fig. 4 the ends of the bars 40 are brought into engagement with the stops 65 which limits the rearward position of the string support 42. The slide 31 then moves rearwardly relative to the bars 40 and the cams 74 are moved out of engagement with the cam surfaces 73 upon the lever 70, thereby permitting the string guide 68 to be returned from the position shown in Fig. 8 to that in Fig. 7 upon the string support 42. As the slide 31 moves rearward, the string support 42 and the cam surfaces 41 move away from the templet 55 and permit the latter to move from the position shown in Fig. 8 to that shown in Fig. 7. This movement of the templet facilitates removal of the handle H therefrom after the handle has been secured to the bag. It will be understood, however, that the construction may be such that the templet will remain at all times 55 in its operative position as shown in Fig. 8. The machine is now in condition to repeat the cycle of operations above described.

We claim:

1. In a machine for securing a string handle to a bag, in combination, a templet, a movable string guide adapted to position string adjacent said templet and in the plane thereof, means for feeding string to said guide, and means for moving said guide out of said plane and for moving said string in engagement with said templet.
2. In a machine for securing a string handle to a bag, in combination, a templet, a movable string guide adapted to position string adjacent said templet and in the plane thereof, means for

feeding string to said guide, means for moving said guide out of said plane and for moving said string in engagement with said templet, and means for maintaining said string in said plane as and when said guide is moved out of said plane. 5

3. In a machine for securing a string handle to a bag, in combination, a templet, a slide movable toward and away from said templet, a string holder slidably mounted upon said slide, means for supplying a desired length of string upon 10 said holder, said slide and string holder being adapted to cooperate to position the length of string in desired relation to said templet, means tending to resist movement of said holder relative to said slide, and a stop for positioning said 15 string holder in desired relation to said supplying means as said slide is moved to its position away from said templet.

4. In a machine for securing a string handle to a bag, in combination, a templet, a slide movable toward and away from said templet, a string holder slidably mounted upon said slide, means tending to resist movement of said holder relative to said slide, a movable string guide adapted to position a length of string upon said string holder, 20 a stop for positioning said string holder in predetermined position as said slide is moved to its position away from said templet, means for feeding string to said guide, and means for moving said guide away from said string holder, said slide and string holder being adapted to cooperate 25 to position a length of string in desired relation to said templet.

5. In a machine for securing a string handle to a bag, in combination, a templet, a slide movable toward and away from said templet and adapted to position string in desired relation to said templet, a movable string guide adapted to position a length of string between said slide and templet, and means operative to move said guide 30 out of the path of said slide as the latter is moved toward said templet. 35

6. In a machine for securing a string handle to a bag, in combination, a support for string, a member reciprocable along said support, means tending to move said member into feeding engagement with said string, and means including a stationary guide rail permitting said member to grip and feed said string as said member is moved in one direction between two predetermined 45 spaced points and for holding said member out of feeding engagement with said string when said member is moved in the opposite direction between said spaced points. 50

7. In a machine for securing a string handle to a bag, in combination, a support for string, a member reciprocable along said support, means for causing said member to grip and feed said string as said member is moved in one direction and for releasing said string as said member is moved in the opposite direction, mechanism for cutting said string, and means responsive to the movement of said member for actuating said mechanism subsequent to each feeding operation of said member. 55

CARLETON G. EATON.
